METHOD OF EFFECTING COMBUSTION OF
FLUID FUEL

Lyman C. Huff, Winnetka, Ill.

Application March 12, 1930, Serial No. 435,144

2 Claims. (Cl. 158—117.5)

This invention relates to improvements in a method and means for burning fluid fuel in a furnace, and in one specific embodiment relates to the burning of fuel oil in domestic furnaces. Among the difficulties encountered in the burning of oil in domestic furnaces may be mentioned, noise, difficulty in obtaining complete combustion and the clogging or coking of the burners, the latter being particularly true when heavy fuel oil is used.

In many of the burner constructions heretofore devised, in order to suitably atomize the fuel, the fuel was forced under pressure through a nozzle having a small orifice. Because of the restricted area of the orifice the use of heavy oil was not always feasible, and in addition, because of the intense heat existent at the orifice, the oil would destructively distill, producing pitches and coke therein and clogging the nozzle. This, of course, necessitated the frequent dismantling and cleaning of the burner.

Accordingly, one of the salient features of the present invention resides in a means and method of injecting oil fuel into the combustion chamber of a furnace under such conditions that, although a heavy fuel oil is used, the nozzle will not overheat and form undesirable coke or pitch therein nor will the oil clog the nozzle.

Another important feature of the present invention resides in the efficient method of admixing the air and fuel to produce perfect combustion of the fuel in the combustion chamber. In addition, the air used for atomizing the fuel may also be utilized to cool the fuel nozzle. Further, the direction, quantity and velocity of the air may be varied at will and to suit conditions.

Briefly described, the invention comprises establishing a stream of air under pressure, controllably passing said air in the vicinity of a fuel discharge nozzle in such a manner as to atomize the oil issuing therefrom and completely surrounding said atomized fuel with a film of air, and subjecting said mixture to both radiant and convection heat, thereby effecting complete combustion of the fuel. The passage of the air in the vicinity of the fuel discharge nozzle cools said nozzle and prevents overheating thereof.

The instrumentalities involved in my invention are susceptible to ready adjustment and regulation; are quickly demountable and interchangeable; can be operated simply and efficiently; and can be constructed economically and readily marketed.

Other and further important objects of the in-

vention will be apparent from the accompanying drawings and following detail description.

In the drawings, Fig. 1 is a side elevation, partly in section, showing the arrangement of apparatus suitable for carrying out my invention.

Fig. 2 is a sectional view taken on the line 2—2 of Fig. 1.

Fig. 3 is a detail sectional elevation, illustrating the burner proper.

Fig. 4 is a front elevational view of the burner, as shown in Fig. 3.

Referring in detail to the drawings, 1 indicates a furnace having walls 2 of suitable insulating material. The furnace 1 may take the form of a hot air furnace, a hot water, or steam furnace or in general, any type of heating furnace used for industrial or domestic purposes. Furnace 1 may be provided with a combustion chamber 3, having walls 4 constructed of refractory material such as firebrick, plastic firebrick or the like, or if desired, the walls 4 may be constructed of a heat resisting metal such as chrome nickel steel or some material having like characteristics. The cross-sectional contour of the combustion chamber 3 may be of any desirable form, but as will hereinafter be more fully brought out, a curvilinear contour may be preferable. A plurality of piers 5 may be disposed in the chamber 3, as shown best in Fig. 2. The piers 5 may be constructed of a material similar to the material comprising the combustion chamber walls 4. The piers, if so desired, may be made adjustable so as to vary the circulatory path of the combustion gases. A cover 6 of the same material may be mounted upon the top of the piers 5 in such a manner as to bridge the space included therebetween.

An aperture 7 is provided in the wall 4 of the combustion chamber 3 and in the wall 2 of the furnace 1. The wall 4 may extend inwardly, as shown best at 8 in Fig. 2, in the vicinity of the aperture 7, the contour of the wall 4 at this point conforming more or less to the contour of the ends of the piers 5. The upper portion of the combustion chamber wall 4 may be curved inwardly as shown at 9 in Fig. 1 so as to direct the combustion gas circulating in the chamber 3 and prevent the gas from contacting the cold walls 2 of the furnace proper.

A blower 10 driven by motor 11 may be mounted upon a suitable platform or support 12 adjacent the furnace 1. The blower 10 may be adapted to discharge air through a conduit 13 controlled by damper 13' which terminates in a nozzle-like element 14 positioned in the aperture 55

7. A worn gear 15 may be mounted upon the end of the blower shaft 16 and is adapted to turn therewith. The gear 15 may mesh with a worm wheel 17 mounted upon shaft 18 of fuel pump 19. 5
5 The pump 19 may be of conventional design suitable for the pumping of oils of various viscosities from light oils to heavy fuel oils.

Oil may be drawn from a suitable source of supply (not shown) through intake pipe 20 and 10 pump 19 and may be discharged through pipe 21 to pipe 22. The pipe 22 may be connected into the conduit 13 through a removable plate 23, the lower portion of said pipe being adapted to discharge adjacent the nozzle 14, which will 15 be hereinafter more fully described. The upper end of the pipe 22 may be bent in the form of a U 24 and is open to the atmosphere. A step-up transformer 25 may be mounted upon the support 12, the high tension leads 26 therefrom passing into the conduit 13 and to a sparking device 20 (not shown) suitably positioned in the discharge opening of the nozzle 14.

Referring particularly to Figs. 3 and 4, detail views of the nozzle 14 are shown. The end of the 25 nozzle 14 is contracted inwardly restricting the area of the conduit 13. A lower segment 27 of the nozzle may be hinged at 28 and by means of the screw 29 may be locked at various angular positions. A spider 30 is removably positioned 30 at the end of the nozzle 14 and may be provided with a central downwardly sloping conduit 31 into which the discharge end of the fuel pipe 22 connects. Radiating from the conduit 31 as a center is a plurality of fins or extensions 32, the 35 outer ends of which terminate adjacent the inner surface of the nozzle 14. A baffle or air foil 33 may be mounted upon a plurality of the fins 32 and may provide air passageways between the foil and the bottom of the nozzle and between 40 the foil and the lower side of the conduit 31, designated as 34 and 35, respectively. Each of the fins 32 may be provided with adjustable dampers 36.

In carrying out my invention the motor 11 may 45 be energized by suitable switching means (not shown) or, if desired, the motor may be thermostatically controlled. Air is forced by the blower 10 through the conduit 13 and issues from the nozzle 14. Simultaneously, fuel is delivered from 50 the pump 19 through pipe 21 and pipe 22 to the conduit 31 and in addition a quantity of air will be drawn into the pipe 22 through the opening at the U bend 24. The sparking means (not shown) may be turned on and the mixture of fuel and 55 air issuing from the conduit 31 and the air issuing from the nozzle 14 per se will be ignited.

As has been hereinbefore described, the conduit 31 is sloped downwardly so that oil issuing from the pipe 22 will flow by gravity down the inclined 60 lower surface of said conduit. The conduit 31 may be formed egg-shaped in section providing a channel 37 at the lower portion thereof. By this provision the fuel flowing through the conduit is concentrated and channelled at the bottom of the 65 conduit, thus increasing its velocity of flow. The oil upon flowing through the channel 37 reaches the downwardly extending tip 38 from which the fuel drips. The drops of fuel as they form on the tip 38 are caught by the stream of air issuing from 70 the passages 34 and are carried upwardly and outwardly into the combustion chamber 3. It can be readily observed that the air issuing from the passages 34 and 35, due to the peculiar shape of the nozzle 14, is focused, as it were, along one 75 line in the combustion chamber, as indicated by

the arrows 39 in Fig. 3. It can also be readily seen that the fuel picked up by the air streams issuing from the passageways 34 will be carried by said air to the common point 39 and from there the united streams surrounding the suspended fuel pass on into the combustion chamber. The downwardly extending tip 38 causes the air issuing from the passage 35 to eddy thereby tending to agitate the suspended fuel, breaking it up into a fine droplet form. By the provision of the adjustable lip 27 the angle of the stream issuing from the passageway 34 may be varied as desired. 10

It will be observed that fuel which may drip from the tip 38 will not be caught by the lip 27 inasmuch as said lip does not extend as far into the combustion chamber as the tip 38. Hence, the drip of fuel from the tip 38 will fall to the bottom of the combustion chamber 3 and may be removed therefrom through the drain 40. A safety trip bucket (not shown) may be positioned beneath the discharge of the drain 40.

As has been hereinbefore mentioned, one of the most troublesome features existent in oil burner nozzles heretofore devised, comprises the overheating of the fuel orifice and the consequent 25 formation of pitch or coke-like material which clog said orifice. This is particularly true when heavy oils are used. To obviate this disadvantageous feature, particular attention has been directed to the cooling of the fuel conduit 31. The 30 provision of the fins 32 tends to remove heat from the conduit 31 by conduction, the heat being carried from the fins by the passage of the air through the various passageways 34 and 35. In addition, the air foil or baffle 33 directs a stream 35 of air into intimate contact with the lower portion of the conduit, further cooling said conduit. A further provision for cooling resides in the novel design of the face of the conduit 31, it being 40 readily seen that no flat surfaces are exposed to the heat from the combustion chamber 3.

In all oil burner nozzles heretofore devised, overheating of the fuel orifice and the resulting formation of coke or pitch therein, is most apt 45 to occur when the blower is stopped. It is obvious that, at the moment of stopping the blower, a quantity of fuel will remain in the fuel orifice, and inasmuch as no air is provided for cooling, the radiant heat from the combustion chamber soon heats the orifice to a high temperature thereby intensely heating the oil and forming pitch and carbon in the orifice. To obviate this difficulty suitable switching or relay means has sometimes been provided to continue the operation of the blower a short time after the fuel is shut off. 50 The objectionable feature of this operation is, that the excess air delivered to the furnace tends to cool the same, thereby reducing its efficiency. 55

In my invention, the blower may be shut off simultaneously with the shutting off of the fuel, 60 the cooling arrangement being so designed that natural draft passing through the nozzle 14 is sufficient to properly cool the conduit 31. Of course, if desired, the blower may be shut off after shutting off of the fuel, in which case a 65 suitable disconnecting means (not shown) may be provided between the blower shaft 16 and the pump shaft 18.

The dampers 36 which control the flow of air 70 through the various passageways may be adjusted to suit varying conditions of firing, fuel and blower pressure. These adjustments are usually determined and made previous to operation. It can be readily seen, that the spider 30 can be 75 readily removed from the nozzle 14 merely by dis-

connecting a portion of the pipe 22 and removing the member 23 and spider 30 as a unit. Thus, the readjustment of the dampers 36 can be readily accomplished, or if necessary, the spider 5 30 may be conveniently repaired or cleaned.

Referring particularly to Fig. 2, the stream of air and oil discharged from the tip of the burner may be projected into the combustion chamber 3 between the piers 5. A jetting action is thereby 10 accomplished inasmuch as a Venturi-like neck 41 is provided between the piers 5 the cover 6 and the bottom of the combustion chamber 3. By this 15 jetting action, hot gases in the combustion chamber may be induced into the neck 41 and caused to recirculate through it as indicated by arrows 42. Thus, hot gases may be brought into contact with the 20 stream of air and oil, heating them to a high temperature. The recirculated gases further keep the inner surfaces of the neck 41 hot so that these surfaces will radiate more heat through the air stream and to the droplets of oil. The recirculated gases likewise radiate heat directly to the 25 droplets of oil.

It will, therefore, be seen that the droplets of oil which are carried suspended in the center or core of the air stream are heated, and may be caused to vaporize while in suspension and surrounded by a stream of air. Upon vaporizing, 30 combustion takes place under the most ideal conditions, as the oil vapors, when expanding, break through the surrounding stream of air, thus mixing thoroughly with it, and affording good combustion.

Any unburned vapor has an opportunity to 35 again be brought in contact with a fresh supply of air by the recirculating features afforded in the combustion chamber and thereby be completely burned.

The jetting action of the combination of burner 40 14 and combustion chamber 3 imparts a high velocity to the gases circulating in the combustion chamber, thereby affording every opportunity for oil vapors and air to become thoroughly mixed, and combustion made complete before the hot 45 gases pass upwardly through the boiler or furnace 1.

By so effectively completing combustion in this manner, maximum temperatures are maintained in the combustion chamber with a minimum 50 amount of excess air for combustion, which substantially increases the amount of radiant heat given off. The efficiency of the boiler or furnace will, therefore, be greatly increased, first, because 55 large amounts of excess air for combustion are eliminated and second, because more radiant heat is given off from the combustion chamber because of the higher temperature maintained therein.

It is apparent that herein is provided a method 60 and means for effecting substantially perfect combustion of extremely heavy oils. Provision is made for most thoroughly cooling the oil stream as it flows through the tip of the burner. The oil does not come in contact with any hot metal surface as it leaves the burner. It is simply caused 65 to flow on to a stream of air which keeps it in suspension and carries it into the combustion chamber where it is quickly heated by radiant heat from the recirculated gases and chamber walls

and vaporizes before contacting directly with any part of the combustion chamber. The radiant heat passes through the stream of air surrounding the oil droplets without substantially losing any heat to the air. Therefore, all the radiant heat is 5 available to heat and vaporize the oil. The incoming air, however, is heated by contacting directly with the hot recirculated gases and is, therefore, heated by convection. In this manner, substantially perfect combustion is effected even 10 with the use of extremely heavy fuel oils.

If desired, the spider 30 may be smoothly ground and then plated with a bright, smooth, metallic substance, such as for example, chromium or nickel and then highly polished. The 15 bright, smooth, plated surface will reflect the radiant heat away from the spider and will further prevent the conduit 31 and tip 38 from attaining a temperature sufficiently high to distill the oil to pitch or break it down to carbon forming 20 particles.

It can be readily seen that due to the cone-shaped formation of the air, as illustrated in Fig. 3 of the drawings, as the same leaves the passages of the nozzle 14, (the apex of the cone being at 25 39), a zone of reduced pressure exists in the interior of the cone. Hence, the vaporization of the fuel entrained in the air passing from the conduits 34 is facilitated, further tending to promote perfect combustion. 30

In order to facilitate the mixing of air and fuel, the fins 32 may be inclined at an angle to the axis of the pipe 31, hence imparting a swirling motion to the air discharged from the nozzle 14.

I am aware that many other modifications may 35 be made and carried out in connection with my invention without departing from the spirit thereof, hence I do not wish to be limited except as necessitated by the prior art.

I claim as my invention:

1. The method of burning liquid fuel which includes introducing liquid fuel into a combustion chamber with a supply of air, introducing a second supply of air into said combustion chamber to atomize said fuel, said second supply of air substantially enveloping said fuel and said first mentioned supply of air, introducing said air and fuel into said combustion chamber, subjecting the mixture of air and fuel to heat whereby said fuel is vaporized and thoroughly mixed with the air, causing combustion of the mixture, diverting a portion of the resulting hot gases of combustion and recirculating the same into contact with a freshly admitted supply of fuel and air whereby the freshly admitted air and fuel is heated. 55

2. A method of effecting substantially complete combustion of liquid fuel which includes discharging liquid fuel into a combustion zone together with a supply of air, introducing a second supply of air into said combustion zone a portion of which atomizes said fuel at the point of introduction of the air and fuel into said combustion zone and uniting the remaining air of said second supply of air and the fuel and air mixture within the combustion zone remote from the point of introduction of the air and fuel into the combustion zone, and subjecting said mixture to radiant heat. 65

LYMAN C. HUFF.
